Primary Examiner — Mary Ann Calabrese(74) *Attorney, Agent, or Firm* — TraskBritt(57) **CLAIM**

The ornamental design for a bassinet, as shown and described.

DESCRIPTION

FIG. 1 is a first perspective view of a bassinet showing my new design;

FIG. 2 is a second perspective view thereof;

FIG. 3 is a perspective bottom view thereof;

FIG. 4 is a top view thereof;

FIG. 5 is a right rear perspective view thereof, but shown in the folded position with the handle removed;

FIG. 6 is a left rear perspective view thereof; and,

FIG. 7 is a bottom perspective view thereof.

Broken-line disclosure is understood to represent portions of the article in which the claimed design is embodied, but which form no part of the claimed design.

1 Claim, 6 Drawing Sheets(56)
